UNITED STATES PATENT OFFICE

155,933

DESIGN FOR A VASE

Tatsuko Shinno, Larchmont, N. Y.

Application October 2, 1946, Serial No. 133,705

Term of patent 14 years

(Cl. D29—28)

To all whom it may concern:

Be it known that I, Tatsuko Shinno, a citizen of the United States, residing at Larchmont, county of Westchester, and State of New York, have invented a new, original, and ornamental Design for a Vase, of which the following is a specification, reference being had to the accompanying drawing, forming part thereof.

Fig. 1 is a perspective view of a vase, showing my new design; and

Fig. 2 is a top plan view thereof.

I claim:

The ornamental design for a vase, as shown.
TATSUKO SHINNO.
